KITE STRING REEL

Donald B. Parsons, P.O. Box 4985,
Santa Fe, N. Mex. 87501

Filed Jan. 27, 1969, Ser. No. 15,528

Term of patent 7 years

Int. Cl. D8—03

U.S. Cl. D8—220

The figure is a plan view of the kite string reel, showing the new design; the reel is of a conventional thickness. The broken lines are for illustrative purposes only.

I claim:

The ornamental design for a kite string reel, as shown and described.
